E. V. BOWE

COMBINATION CLOTHES HANGER AND TROUSERS CREASER

Filed March 20, 1922

D. B. C. INVENTOR.
EDWARD V. BOWE.
BY A. B. Bowma ATTORNEY

UNITED STATES PATENT OFFICE.

EDWARD V. BOWE, OF SAN DIEGO, CALIFORNIA.

COMBINATION CLOTHES HANGER AND TROUSERS CREASER.

Application filed March 20, 1922. Serial No. 545,079.

To all whom it may concern:

Be it known that EDWARD V. BOWE, a subject of the King of England, residing at San Diego, in the county of San Diego and 5 State of California, has invented certain new and useful Combination Clothes Hangers and Trouser Creasers, of which the following is a specification.

My invention relates to a combined trousers creaser and clothes hanger and the objects of my invention are: first, to provide a 10 novel and efficient means for creasing trousers; second, to provide a device of this class which will crease the trousers with a minimum amount of attention, labor and 15 expense; third, to provide a device of this class by which newly creased trousers can be had each morning; fourth, to provide a device of this class which is adaptable to all 20 sizes of trousers without unnecessary adjustment; fifth, to provide a device of this class which inherently keeps the trousers stretched and pressed; sixth, to provide a 25 device of this class which can be folded up into a small compact parcel and conveniently carried in a suitcase or the like; seventh, to provide a device of this class which provides a 30 convenient trousers and coat hanger; eighth, to provide a novelly constructed trousers creaser and coat hanger, and ninth, to provide a device of this class which is very 35 simple and economical of construction, durable, easy to operate and which will not readily deteriorate or get out of order.

With these and other objects in view as will appear hereinafter my invention consists of certain novel features of construction, combination and arrangement of parts and portions as will be hereinafter described 40 in detail and particularly set forth in the appended claims reference being had to the accompanying drawings and to the characters of reference thereon which form a part of this application in which:

Figure 1 is a front elevational view of my device with a pair of trousers clamped therein and with one section opened up showing the operation of the trousers supports; Fig. 2 is a side elevational view thereof showing 45 by dotted lines the operation of folding up my device; Fig. 3 is an enlarged detail end view of a fragmentary portion of my device showing by solid and dotted lines various operative positions thereof; Fig. 4 is a rear elevational view of the device folded up;

Fig. 5 is a fragmentary elevational view of a modification of my device showing another means of hanging a coat thereon; Fig. 6 is a rear elevational view of the modified form of my device folded up and Fig. 7 is 60 an elevational view taken at a right angle thereto.

Like characters of reference refer to similar parts and portions throughout the several views of the drawings.

The stationary supports 1, movable supports 2, creasing members 3 and 4, hinges 5, tension members 6 and 7, handle members 8, links 9, and the hanger 10 constitute the 70 principal parts and portions of my device in one form.

My device consists of two units of substantially stationary support members 1 secured together by hinges 5, each unit being shiftably mounted relatively to each other 75 at one end thereof on the hanger 10. Each stationary or support member 1 is provided with an oppositely disposed movable member 2, movable relatively to said stationary support member. Said support members 1 and 2 are provided with creasing members 3 and 4 respectively secured thereto in a suitable manner and adjacent each other when in operative position and consists preferably of strips of soft wood capable of 80 absorbing moisture from the dampened portions of the trousers. Said creasing members are provided with means for permitting the excess of water or moisture to escape and by the same means permitting air to come 85 into contact with the moistened portion of the trousers and may consist of grooves 3^a and 4^a extending transversely across the inside faces of said creasing members. Each pair of support members 1 and 2 are provided 90 with U-shaped tension members 6 and 7 respectively, the former being permanently secured in the member 1, while the latter is reciprocably mounted transversely in the member 2. Said tension members are pivotally and eccentrically mounted in the handle member 8. A link 9 is provided on each leg of each pair of U-shaped tension members adapted to take up the compression 95 stresses due to the clamping of a trousers 100 between the creasing members. The permanently secured tension member 6 is preferably bent outwardly or away from the opposite tension member 7 so that the link 9 when shifted across the support members 110

or creasing members as shown best in Fig. 3 of the drawings, said link will not readily slip back, and therefore release the pressure caused by the same. The hanger 10 connecting the two units of support and creasing members is preferably shaped substantially as shown in Figs. 1 and 2 of the drawings, having a slightly upward inclination near the ends of the lower portion thereof 10 adapted to receive the two units of support members thereon at their normal upper ends and spread the opposite normal lower ends apart to assume the position of the creased edges of the inverted trousers clamped therebetween and stretch the same. Said units of support members are retained in said spread position on said hanger by the clips 14 frictionally engaging the lower portion thereof. 15

It will be noted that when my apparatus 20 is folded up as shown by dotted lines in Fig. 2 of the drawings and also in Fig. 4 of the drawings that the hanger 10 is swung around about its lower portion and fits into and is retained by the notches 2^a in the normally lower movable support members. It 25 will be also noted that a collar or stop 15 is secured on the lower portion of said hanger member to space the two units of support members centrally thereon when folded up. 30

It will be further noted that by turning the handle 8 counter-clockwise as shown in Fig. 3 of the drawings thereby turning the upper edge of the handle 8 inwardly toward the supporting members, and since the tension members 6 and 7 are mounted eccentrically therein and since the tension member 7 is mounted reciprocably in the movable support member 2, said tension member 7 will be shifted transversely with respect to 35 the movable support member 2. The tension member 7 being also shifted from the position shown by A' to the position shown by B' will relieve the tension on the link 9 permitting the same to be shifted from its 40 position indicated by A'' to the position indicated by B''. It will be further noted that after the handle is shifted from the position A to the position B as shown in Fig. 3 of the drawings, the movable support member 2 may readily be shifted or moved about the end of the tension member 6 mounted in said handle 8 so that said support member 2 with its creasing member 4 will be moved from and clear the support 45 member 1 and its corresponding creasing member 3, taking with it the tension member 7 mounted therein and the handle 8, assuming respectively the positions C' and C. The link 9 will be automatically shifted from the position B'' to C'' as shown in the drawings. 50

In the modified form of my device shown in Figs. 5, 6 and 7 of the drawings, I have provided the hanger 11 with inwardly extended portions 11^a. Mounted on said

hanger 11 at the inwardly extended portions thereof is a channel shaped member 12 slightly shiftable thereon, and extending some distance outwardly from said mounting. Elongated U-shaped coat hanger members 13 are pivotally mounted in the flange portions of the extended portions of said channel member 12. The rear portion of the U-shaped hanger member 13 is provided at the end projecting through the channel member 12 with a loop portion 13^a adapted to catch under one leg of the U-shaped creasing members 7 when the device is folded up as shown best in Figs. 6 and 7 of the drawings and retain the device in said folded up position. The hanger members 13 are curved outwardly at their end 13^b to conform with the curvature of the coat lines. 70 75 80

Though I have shown and described a particular construction, combination and arrangement of parts and portions and a certain modification thereof I do not wish to be limited to this particular construction, combination and arrangement nor to the modifications thereof but desire to include in the scope of my invention the construction, combination and arrangement substantially as set forth in the appended claims. 85 90 95

Having thus described my invention what I claim as new and desire to secure by Letters Patent is:

1. In a device of the class described, a hanger member, creasing members shiftable mounted on the lower portion of said hanger member, other creasing members oppositely disposed to said former creasing members and movable therewith, a handle, tension members secured in each of said oppositely disposed creasing members at one end and pivotally and eccentrically mounted in said handle at the other end and means in connection with said tension members adapted to secure said creasing members in clamped position with each other. 100 105 110

2. In a device of the class described, creasing members hinged at their ends with each other, a clothes hanger member shiftable mounted with respect to the free ends of one of said creasing members, other creasing members oppositely disposed to and movable with respect to said former creasing members and means adapted to secure said oppositely disposed creasing members in clamped position with each other. 115

3. In a device of the class described, creasing members hinged at their ends with each other, a clothes hanger member shiftable mounted with respect to the free ends of one of said creasing members, other creasing members oppositely disposed to and movable with respect to said former creasing members, tension members secured to each of said oppositely disposed members adapted to provide variable and flexible means for clamping said creasing members with each 120 125 130

other, and means for securing said creasing members in said variable and flexible clamped position with each other.

4. In a device of the class described, creasing members hinged at their ends with each other, a clothes hanger member shiftably mounted and with respect to the free ends of one of said creasing members, other creasing members oppositely disposed to and movable with respect to said former creasing members, a handle, tension members secured to each of said oppositely disposed

creasing members at one end and pivotally and eccentrically mounted in said handle in the other end and means secured on said handle member adapted to receive said oppositely disposed creasing members in variable and flexible clamped position with each other. 15

In testimony whereof, I have hereunto set 20
my hand at San Diego, California, this 11th
day of March, 1922.

EDWARD V. BOWE.
